KIT FOR SORTING CARDS

Merrill C. Nolan, Washington, D. C., assignor to
The McBee Company, Athens, Ohio, a corporation

Application August 8, 1949, Serial No. 109,108

6 Claims. (Cl. 129—1)

1

This invention relates to a complete kit or unit for employment with statistical cards. More particularly, it relates to a complete kit or unit adapted to field use with marginally perforated cards of the "Keysort" type.

It is an object of the present invention to provide a kit or unit of the character described which, when not in use, can be readily folded into a compact kit and which, when it is desired to use the same, is easily set up and easily operated.

It is a further and a particular object of the invention to provide a kit constituting a complete unit, whereby marginally perforated "Keysort" cards of the character described can be manipulated, entries can be made thereon and the cards can be sorted as desired, such kit also folding up into a neat, compact unit when not in use.

These and other objects of the invention will be apparent from the ensuing description and the appended claims.

The invention is exemplified in the following description and illustrated by way of example in the accompanying drawings, in which:

Fig. 1 is a perspective view of the kit shown in folded condition.

Fig. 2 is a similar view showing, however, the first step in unfolding and setting up the kit.

Fig. 3 is a perspective view showing the kit unfolded but with certain of the interior elements in folded, inoperative condition.

Figs. 4 and 5 are perspective views, taken from the front and back, respectively, showing the kit in the final stages of setting it up for operation.

Fig. 6 is a fragmentary view of the kit, on a larger scale, showing the same as being used for posting operations.

Fig. 7 is a fragmentary view of the kit showing the manner of using it for sorting cards.

Referring now to the drawings, a kit or field unit is shown and is generally designated as 9. As illustrated, the kit 9 comprises a case 10 formed with a hinged end portion 11 and a hinged flap 12 which, when the kit is folded, are secured by means of fasteners 14 to a cover portion 15. The case 10 is also formed with hinged, nesting side portions 16, with a fixed side portion 16a and with an end portion 17 and a bottom portion 18.

As illustrated in Fig. 2, the end portion 11 and the flap 12 when unfolded and laid flat, provide a shelf to receive and allow convenient access to tools and appurtenances which are held by straps 19 and 20. As illustrated, these tools

2

and appurtenances comprise a hand punch 25, a master sorting tumbler 26, pencils 27 and sorting needles 28, the purpose and function of which are explained hereinafter.

Referring now to Fig. 3, the kit is there shown as being unfolded but with the inner parts still in inoperative condition. The cover 15, the bottom portion 18 and other elements of the case 10 provide a convenient base and framework for supporting the other operating elements of the kit. The base so provided will be designated hereinafter by the numeral 30.

It will be seen that an inner frame member or bracket 40 is provided which is fixed to the base 30 adjacent the rear edge and to one side thereof. The bracket 40 is formed with forwardly extending ears 41 and a bail member 42 is provided which is pivotally connected at its ends to the ears 41. Tension springs 43 are also provided, each being fixed at one end to the bail 42 and at the opposite end to an ear 41, so as normally to urge the bail in a downward position for a purpose explained hereinafter.

Referring now to Figs. 4 and 5 as well as 25 to Fig. 3, a ledger tray generally designated as 44 is provided. This ledger tray is formed by a flat, folded member made of cardboard, composition material or any other suitable material and it comprises a rear section 45, a card supporting section 46 hingedly connected thereto and at 47 to the base 30, a forward section 49 and an end section 50 which limits against a stop bracket 51 fixed to the base 30.

To the right of the ledger tray 44 as viewed 35 in Figs. 3 and 4, there is provided a card alignment member 54 having a shelf 55, a flat base portion 56 disposed at right angles thereto and a guide portion 57 along one edge thereof. The alignment element 54 is hingedly connected at 40 58 to the base 30. Forwardly of the alignment member 54 a soft or resilient pad 60 is fixed to the base 30 to receive a pad 61 of note paper. As is also shown, angle springs 62 and 63 are pivotally supported upon the base 30 for a purpose explained hereinafter.

In operation, the kit 10 is employed and manipulated as follows: First, of course, the flap 12 and end portion 11 are unlatched and laid out as illustrated in Fig. 2 and then the cover and bottom 50 portions 15 and 18 are laid out as illustrated in Fig. 3. It will be noted that when in this position and also, of course, when the kit is folded up, as shown in Figs. 1 and 2, a supply of ledger cards 64 are neatly stacked between the ears 41 of bracket 40 and are held firmly in place by means

of the folded ledger tray 44 and the spring biased bail member 42. It will also be seen that the alignment member 54 and the paper pad 61 are held firmly in position by means of the angle springs 62 and 63.

As shown in Figs. 4 and 5, the ledger tray 44 is unfolded with the ledger cards 64 supported thereon in a convenient position for inspection and other operations. As is best shown in Fig. 5, when the ledger tray has been set up, the bail 42 serves to brace the rear section 45 of the ledger tray and, in cooperation with the stop bracket 51, to fix the ledger tray firmly in operative position. As shown in Fig. 5, the alignment member is pivoted to a suitably inclined position and is supported and latched therein by means of an arm 65 pivotally connected thereto at 66. The kit 9 is now in complete readiness for operation.

Referring to Figs. 6 and 7, the ledger cards 64 have each a front or face portion 64a and a rear portion 64b. These ledger cards are of known type and are formed with marginal perforations 70 along all four edges, arranged in parallel inner and outer rows. As is also indicated, each ledger card is provided with ruled lines 71 and with any suitable indicia (not shown) for the purpose of entry of information on both the faces of the card. As is well known in the art, ledger cards of this type, such as the well known "Keysort" cards, are notched or slotted at 72 along their edges in registry with the marginal perforations, for the purpose of coding and selecting the cards.

As shown in Fig. 6, a stack of the ledger cards can be conveniently posted on either or both faces thereof, by folding the forward and end sections 49 and 58 of the ledger tray so as to lie flat, thus allowing convenient access for posting entries on the front faces of a stack of cards supported by the ledger tray. Posting on the rear faces of the cards is accomplished by supporting a stack of cards on the alignment member 54. Obviously, posting on both sides of the cards, or left and right hand posting, can be carried out conveniently by this arrangement.

It will be apparent, of course, that if it is desired to run quickly through a stack of ledger cards for visual inspection and selection of the cards, the cards may be stacked in the ledger tray 44 with either face forward, as desired. In this case the ledger tray 44 will be completely set up as shown in Figs. 4 and 5, and the operator need only flip the cards forwardly as he runs through them.

For purposes of mechanical selection of cards, the alignment element 54 is employed. Thus, a stack of ledger cards is placed on the shelf 55 and allowed to rest against the base portion 56. The stack of cards is then pushed against the guide portion 57 so that the edges of the cards are flush. The marginal perforations 70 are thus brought into precise registry, so that multiple selection by means of the sorting needles 28 or offsetting by means of the master sorting tumbler 26 may be carried out. Offsetting by means of the master sorting tumbler 26 is illustrated by Fig. 7, and it will be seen that in this instance, the ledger cards, after being aligned on the alignment member 54 and after insertion of the sorting tumbler through a selected perforation 70, are transferred to the ledger tray for greater convenience of operation.

It will be apparent that the tools and appurtenances carried on the end section or shelf 11 are conveniently located and that they permit the carrying out of a multiplicity of operations. Use of the sorting tumbler 26 and sorting needles 28

has been mentioned. The pencils 27 are conveniently located for posting and the hand punch 25 for notching and slotting the cards.

It will thus be apparent that a kit has been provided which collapses and folds into a very compact, neat appearing package, and that when it is unfolded and set up it is adapted to a multiplicity of operations. Thus, reading or scanning of cards on both faces thereof is facilitated. Also, left and right-hand turning of the cards for the purpose of posting on both faces thereof or for inspection of both faces thereof is facilitated, and these operations are possible without the necessity of removing any of the cards from the order in which they are stacked. The apparatus also lends itself readily to the operations of posting, offsetting and multiple-needle sorting.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A kit of the character described adapted to posting and sorting of marginally perforated ledger cards and the like, comprising a housing having top and bottom portions adapted to enclose the contents of the kit when folded and to provide a base therefor when unfolded, a foldable ledger tray foldable within the kit and hingedly connected to the housing and unfoldable to provide a support for a stack of ledger cards during posting operations, and an alignment member arranged in side-by-side relationship with said ledger tray, said alignment member being hingedly connected to the housing and being foldable within the kit and including means for supporting it at a suitable angle and guide means along one edge thereof for aligning a stack of cards supported thereon.

2. A kit of the character described adapted to posting and sorting of marginally perforated ledger cards and the like, comprising a housing having top and bottom portions adapted to enclose the contents of the kit when folded and to provide a base therefor when unfolded, a foldable ledger tray foldable within the kit hingedly connected to the housing and unfoldable to provide support for a stack of ledger cards during posting operations, said ledger tray comprising a rear portion adapted when unfolded and set up to support a stack of cards in suitably inclined position, and a forward portion oppositely inclined to provide a support for cards as they are turned over during posting, and an alignment element disposed in side-by-side relationship with said ledger tray, said alignment element being hingedly connected to the housing and being foldable within the kit and being provided with means for supporting it at a suitable angle for supporting a stack of cards and with alignment means along one edge thereof for aligning said stack of cards.

3. A kit of the character described adapted to posting and sorting of marginally perforated ledger cards and the like, comprising a housing having top and bottom portions adapted to enclose the contents of the kit when folded and to provide a base therefor when unfolded, a foldable ledger tray foldable within the kit and unfoldable to provide a support for a stack of ledger cards during posting operations, said ledger tray including a portion adapted to be set at a

suitable angle and to support a stack of cards in suitably inclined position for posting and a forward and oppositely inclined portion adapted to provide support for cards as they are turned over during posting, a bail member and resilient means urging the bail member against said ledger tray to support the same in unfolded, operative position, and a stack of ledger cards for said kit, said ledger cards being encompassed by said ledger tray and being clamped therein by said bail member when the kit is folded.

4. A kit of the character described, comprising a foldable case adapted to enclose the contents of the kit when folded and to provide a base therefor when unfolded, a bracket fixed to the base and having forwardly extending ears, said bracket being adapted to receive a stack of ledger cards between said ears, a stack of ledger cards so received, a foldable ledger tray encompassing said cards when folded and including a rearward portion and a forward portion respectively adapted when the ledger tray is set up to support a stack of cards and to receive cards as they are flipped over, a bail hinged to said bracket, spring means operable to urge the bail against the ledger tray when in folded position to clamp the cards therein and to bear against the ledger tray when in unfolded, set up position to support the same, an alignment member hingedly mounted on said base in side-by-side relationship to the ledger tray, said alignment member having a bottom shelf for supporting a stack of cards and having along one edge a guide member for aligning a stack of cards, and means for supporting the alignment member in inclined position.

5. A kit of the character described adapted to posting and sorting of marginally perforated ledger cards and the like comprising, a housing or case having top and bottom portions adapted to enclose the contents of the kit when folded and to provide a base therefor when unfolded, a foldable ledger tray foldable within the kit and unfoldable to provide a support for a stack of ledger cards during posting operations, said ledger tray comprising a first card support hingedly connected to the housing and swingable against the housing to an inoperative position and therefrom to an inclined operative position, a bracing member hingedly connected to the first card support and swingable beneath the first card support and thereagainst to an inoperative position and therefrom to an operative position, means operatively connecting the bracing member to the housing when the bracing member is in its operative position, a second card support, means hingedly connecting the second card support to the first card support to enable the second card support to be swung to an inoperative position overlying the first card support and therefrom to an inclined operative position, a bracing member

hingedly connected to the second card support and swingable thereagainst to an operative position and therefrom to an inoperative position, means for operatively connecting the last-named bracing member to the housing when the bracing member is in its operative position, and a spring-pressed bail for holding the parts together in inoperative position.

6. A kit of the character described adapted to 10 posting and sorting of marginally perforated ledger cards and the like comprising, a housing or case having top and bottom portions adapted to enclose the contents of the kit when folded and to provide a base therefor when unfolded, a foldable ledger tray foldable within the kit and unfoldable to provide a support for a stack of ledger cards during posting operations, said ledger tray comprising a first card support hingedly connected to the housing and swingable against the housing 15 to an inoperative position and therefrom to an inclined operative position, a bracing member hingedly connected to the first card support and swingable beneath the first card support and thereagainst to an inoperative position and therefrom to an operative position, means operatively connecting and bracing member to the housing when the bracing member is in its operative position, a second card support, means hingedly connecting the second card support to the first card 20 support to enable the second card support to be swung to an inoperative position overlying the first card support and therefrom to an inclined operative position, a bracing member hingedly connected to the second card support and swingable thereagainst to an operative position and therefrom to an inoperative position, means for operatively connecting the last-named bracing member to the housing when the bracing member is in its operative position, a bail member and 25 resilient means urging the bail member against the ledger tray to support the same in unfolded operative position, a stack of ledger cards for said kit, said ledger cards being encompassed by said ledger tray and being clamped therein by said 30 bail member when the kit is folded.

MERRILL C. NOLAN.
